UNITED STATES PATENT OFFICE.

KARL VÖLLER, OF DUSSELDORF, GERMANY.

GUN ADAPTED PREFERABLY FOR USE IN SUBMARINE BOATS.

1,093,504.

Specification of Letters Patent. Patented Apr. 14, 1914.

Application filed June 24, 1913. Serial No. 775,504.

To all whom it may concern:

Be it known that I, KARL VÖLLER, engineer, a subject of the German Emperor, residing at 12 Scharnhorststrasse, Dusseldorf, Germany, have invented certain new and useful Improvements in Guns Adapted Preferably for Use in Submarine Boats; and I do hereby declare the following to be a full, clear, and exact description of the invention, such as will enable others skilled in the art to which it appertains to make and use the same.

My present invention relates to a disappearing gun, that is to say, to a gun that is arranged to be lowered into an inclosing chamber and is thus specially adapted for the use in submarine boats.

More especially my invention relates to that kind of guns answering to the above description, in which the cover provided for closing the said chamber is in operative connection with the gun proper.

According to my invention I connect the cover to the barrel of the gun in such a manner that it partakes of the sliding movements imparted to the gun. By this means I obtain the specific advantage that the bore of the gun can be made comparatively large, for the reason that the mass of the cover is thus added to the recoiling mass of the barrel. According to my invention I attach the cover to a part which is rocked simultaneously with the barrel for the purpose of giving the latter the desired elevation. In guns which have the trunnions placed very far backward, the cover can thus be utilized to form a counterweight. In elevating the gun the center of gravity is rocked around the axis of the trunnions and I make the cover adjustable in such a manner that it can be shifted accordingly and thereby maintain the equilibrium of the system. Such shifting of the cover can be performed by hand and for that purpose index marks may be provided to indicate the required length of the adjustment in every case. But my invention also comprises means for shifting the cover automatically as the barrel is elevated as by means of a cam. By means of locking mechanism the cover can be fixed in the desired position. In cases in which the position of the trunnions is so chosen that their axis passes through the center of gravity

of the rocking system, the weight of the forward part of the gun may be counterbalanced once and for all by the cover without providing means for shifting the latter. If it is preferred to utilize the cover as a shield against projectiles it may be protected with steel armor.

In the accompanying drawing the preferred embodiments of my invention are shown in diagrammatical sectional elevations.

Figure 1 is a sectional elevation illustrating one embodiment of the gun in the operative position in full lines and in the withdrawn position in broken lines. Fig. 2 is a sectional elevation of another embodiment of the invention in the withdrawn position and Fig. 3 a sectional elevation of the same embodiment in an elevated position.

In Fig. 1 *a* represents the deck of a submarine boat. Uprights *b* are provided to support a casing or chamber *a*¹ adapted to receive the gun, when it is withdrawn from the firing position. By means of brackets *d*¹ a cover *c* is fastened to the barrel *d* of the gun. Through the bottom of the casing *a*¹ passes a piston or plunger *f* which moves in a cylinder *g* fed by water pressure, the whole adapted and arranged to raise and lower the gun into and out of the firing position. This latter arrangement forms no part of my present invention and could be replaced by any other adequate means for operating the gun without affecting the nature of my invention. According to the arrangement illustrated the plunger *f* may be simultaneously utilized as a pivot to swing the gun around the horizon.

In the instance illustrated in Fig. 1 the cover *c* is attached to the barrel of the gun. The latter is placed in a sliding support in a manner usual in the art, the slide moving lengthwise in a cradle *h* against the counteraction of a brake cylinder *h*¹ to allow for the necessary recoil movement. Thus the cover *c* takes part in the recoil movement when the gun is fired. The cradle *h* is supported on the upper end of the plunger *f* by means of trunnions *e*. By thus attaching the cover *c* to the gun barrel *d* the recoiling mass is considerably increased and by this means the use of a comparatively large bore becomes possible. On the other hand, upon lowering the gun to close the casing *a*¹ the

weight of the cover is increased by the weight of the gun thus enhancing the pressure of the cover on its seat on the edge of the casing α^1 and producing a more perfect fit against leakage.

In the instance illustrated in Figs. 2 and 3 the cover c , instead of being attached directly to the gun barrel, is attached to the cradle h by means of links i . Rigidly fixed 10 to the cradle h are locking means k adapted to fix the cover in different adjustments. When the gun is lowered, as in the position shown in Fig. 2, the cover is located with relation to the gun in such a position that 15 its weight does not counterbalance the forward part of the rocking system. But by swinging the cover backward on links i and fixing it in the desired position by means of the locking arrangement k , it can be brought 20 into a position in which it exactly counterbalances the weight of the forward end of the gun in any desired elevation. The couple produced by the action of gravity upon the forward end of the gun varies inversely 25 with the elevation and by thus providing means for variously adjusting the cover these variations of the said couple can be equalized.

I do not herein claim the embodiment of 30 my invention shown in Figs. 2 and 3, claims thereto being presented in a concurrent ap-

plication filed October 3, 1913, Serial No. 793,121.

Having thus described my invention what I claim is:

1. In combination with a gun adapted for use in submarine boats, a casing for said gun, a cover for said casing movable vertically with said gun, and means for simultaneously raising and lowering the gun and 40 said cover, said cover being also movable with said gun in the recoil thereof.

2. In combination with a gun adapted for use in submarine boats, a casing for said gun, a cover for said casing carried by said 45 gun and movable therewith on its recoil, and means for raising and lowering said gun.

3. In combination with a submarine boat, a casing extending beneath the deck thereof, a gun adapted to fit in said casing, a cover 50 for the latter capable of being raised and lowered concurrently with the gun, and means for raising and lowering the gun, said cover being also movable with said gun in the recoil thereof.

In testimony whereof, I have signed this specification in the presence of two subscribing witnesses.

KARL VÖLLER.
